UNITED STATES PATENT OFFICE.

FRANK C. KELLER, OF MILWAUKEE, WISCONSIN.

BOTTLE-FILLING MACHINE.

SPECIFICATION forming part of Letters Patent No. 655,443, dated August 7, 1900.

Application filed April 20, 1899. Serial No. 713,704. (No model.)

To all whom it may concern:

Be it known that I, FRANK C. KELLER, a citizen of the United States, residing at Milwaukee, in the county of Milwaukee and State of Wisconsin, have invented certain new and useful Improvements in Bottle-Filling Machines, of which the following is a specification, reference being had to the accompanying drawings, forming a part thereof.

10 The main objects of my invention are to facilitate the bottling of carbonated or effervescent beverages or liquids, to avoid foaming and loss and deterioration of such liquids in the operation of bottling, to economize space, and generally to improve the construction and operation of apparatus of this class.

It consists in certain novel features in the construction and arrangement of component parts of the apparatus, as hereinafter particularly described, and pointed out in the claims.

In the accompanying drawings like letters designate the same parts in the several figures.

25 Figure 1 is a view, partly in side elevation and partly in vertical medial section, of a bottle-filling machine embodying my invention. Fig. 2 is a side elevation and partial vertical section, on a greatly-enlarged scale, of a portion of the rotary reservoir and one of the bottle-holders. Fig. 3 is a horizontal section on the line 3 3, Fig. 2. Fig. 4 is a vertical section on the line 4 4, Fig. 3; and Figs. 5 to 8, inclusive, are detail views of the mechanism 30 for grasping and holding the neck of a bottle in position for filling, Fig. 5 being a horizontal section on the line 5 5, Fig. 6, Fig. 6 a rear elevation and vertical section looking from the right with reference to Fig. 2, and Figs. 7 and 40 8 sections on the lines 7 7 and 8 8, respectively, Fig. 2.

A designates a floor-stand, which may be conveniently made in the form shown in Fig. 1, with a ring a at the upper end, in which is secured an upwardly-extending tube a' and in line therewith a downwardly-extending tubular bearing a^2 , having a lateral liquid-supply connection B within the ring a .

C is a closed reservoir, preferably of cylindrical form, for containing the liquid to be bottled and compressed air or gas above the liquid. It is provided on the underside with

a tubular stem D, which extends loosely through the tube a' of the floor-stand and is supported at its lower end in the bearing a^2 55 upon a packing-ring or washer. The boss on the bottom of the reservoir, into which the upper end of the stem D is screwed, is fitted to turn in the upper end of the tube a' , while the lower end of said stem turns in the bearing a^2 . The reservoir is thus firmly supported, but allowed to turn freely around its central vertical axis. Said reservoir is provided with a detachable cover C', recessed in the under side and formed on the upper side with 60 a central upwardly-projecting tubular neck c. In the neck c is fitted an inverted cup E, having a perforated head at the upper end and an outwardly-extending flange at the lower end. e is a cap threaded upon the upper end of the cup for securing it in place in the neck c and for closing the upper end of said neck. A packing-ring interposed between said cap and the upper end of the neck forms a gas-tight joint. 70

F is a pipe-coupling and valve-chamber centrally and loosely suspended from the head of the cup E. It is formed with two chambers, which are arranged side by side and communicate with each other. One of said 80 chambers is open at its lower end and in it is secured the upper end of a tube G. The other chamber is formed at its lower end with a port and valve-seat and is provided at its upper open end with a screw cap or plug f. 85 A valve H, contained in the latter chamber, normally closes said port and has a stem projecting downwardly through it. The lower end of the tube G is secured in one member g of a coupling located near the bottom of the 90 reservoir C. In the lower end of the same coupling member is secured the upper end of a small tube I. To the other coupling member g' is attached the upper end of a tube J, which extends downwardly therefrom inside 95 of the tubular stem D and outside of the tube I through the tubular bearing a^2 into a chambered fitting K, which has a gas-supply connection L communicating through a passage controlled by a cock l with the chamber k, 100 into which the tube J opens. A waste-cock l' opens out of said chamber. The tube I passes through the chamber k into a chamber k', which is connected by a branch passage l' 105

with the supply connection L. In the chamber k' is loosely fitted a flanged sleeve k^2 , having an opening through the side and closed at its lower end. The lower end of said chamber k' is closed by a gland k^3 , which rests in a socket in the upper end of a screw k^4 , threaded in the ring a of the floor-stand and in line with the bearing a^2 . Packing-rings at the ends of the sleeve k^2 prevent leakage 5 of gas into the chamber k and around the gland k^3 to the atmosphere. The lower end of the tubular bearing a^2 , which is contracted, is inserted in a recess in the upper end of the fitting K around the tube J, suitable packing 10 being interposed between said bearing and fitting to form a gas-tight joint around said tube.

M is an inverted cup-shaped gas holder or bell, which is preferably of cylindrical shape 20 and is provided with a central tubular stem m , open at both ends. The stem m is loosely fitted over a collar g^2 on the upper end of the pipe G and the coupling member g and is adapted to move freely up and down thereon.

25 N is a tube attached at its lower end to the coupling member g' and communicating through a passage therein with the upper end of the tube J. It extends upwardly from said coupling member close to and parallel 30 with the stem m into the upper part of the bell M, where it opens. A weighted lever O, fulcrumed to an arm on the lower end of the cup E, counterbalances the bell M.

P is a valve normally closing a waste-passage c' in the cover of the reservoir C. It is engaged by one end of a lever P', fulcrumed to an arm on the lower end of the cup E and engaged at its other end by a groove or flanges on the upper end of the tubular 40 stem m .

The reservoir C is formed with a number of outwardly-projecting necks c^2 , in the outer ends of which are pivotally mounted bottle-holders and siphons. Each of these siphons 45 consists of a bent tube Q and a nozzle Q'. The tube Q, which is bent downwardly at both ends, is formed or provided at its outer end with a recessed head q , in which is fitted a rubber or other suitable packing-ring for 50 sealing the mouths of bottles held therein, and at its inner end said tube is provided with a valve-chamber containing an upwardly-closing winged valve q' , the downwardly-projecting stem of which is loosely fitted in a 55 flanged sleeve q^2 , which is loosely fitted and movable endwise in said valve-chamber. Said sleeve is provided for the purpose of extending the intake end of the siphon-tube close to the bottom of the reservoir C when 60 said valve is opened. Each tube Q is formed or provided on opposite sides with trunnions fitted and adapted to turn in bearings in an internally-screw-threaded flanged ring c^3 , which is fitted over the outer end of one of 65 the necks c^2 on the reservoir C, as shown in detail in Figs. 3 and 4. The space between said tube and the neck through which it

passes is closed by a flexible diaphragm q^3 , of rubber or other suitable material. This diaphragm is secured around its inner edge to 70 the tube Q between a shoulder and a ring threaded upon said tube, and at its outer edge it is clamped between the end of the neck c^2 and the flanged ring c^3 by means of an externally-threaded and winged ring c^4 , 75 fitted on the outside of said neck. By this means the siphons are made readily detachable from the reservoir for the purpose of cleansing, repair, or inspection. The nozzle Q' passes through a central opening in the 80 head q and the packing-ring contained therein and is secured in the outer end of the lower passage in the tube Q.

R is a valve normally closing a passage in each tube Q leading from the gas-space within the reservoir C into an annular space in the head q around the upper end of the nozzle Q'. This valve is loosely held in a chamber which is formed in the outer end of the tube Q and closed by a screw-cap, affording easy access 90 thereto. A lever r, fulcrumed in the gas-passage of the tube Q, engages at one end with the valve R and projects upwardly at the other end from said passage into the neck c^2 , with which it engages when the outer end 95 of the siphon is depressed. To the lower end of an arm q^4 , on each of the heads q , is adjustably secured a bottle-rest S, adapted to support a bottle in proper position for filling on the adjacent nozzle Q'. 100

T T are jaws hinged together and movable vertically a limited distance upon a tube t, which is loosely guided and movable vertically in an opening in the arm q^4 , approximately parallel with the nozzle Q' of each siphon, as shown in Figs. 1, 2, and 6. These jaws project from said tube outwardly on opposite sides of the nozzle and are adapted to grasp the neck of a bottle placed thereon, and when raised, as hereinafter explained, 110 to force the mouth of the bottle upwardly against the packing-ring in the associated head q , thus hermetically sealing the bottle while it is being filled. The tube t is provided on the back side with an upwardly-projecting wedge t' , which is adapted when forced upwardly to pass between lugs t^2 on the rear ends of the jaws, as shown in Figs. 2, 5, and 6, and thereby force the front ends of the jaws together against the neck of a bottle, at 120 the same time moving them upward against the shoulder on the bottle-neck and forcing the mouth of the bottle against the packing-ring in the head q . 115

A lever U, fulcrumed to the lower end 125 of the arm q^4 , is pivoted at its outer end to the lower end of a rod u, which passes upwardly through the tube t and is retained therein by a cross-pin u' at its upper end. A spring u^2 , surrounding a reduced part of the rod u and bearing at its lower end against a shoulder thereon and at its upper end against a ring or shoulder in the upper end of said tube, constitutes, with said rod and tube, a 130

yielding connection between the lever U and the wedge t' , whereby the closing of the jaws T and their upward movement may be arrested before the lever U reaches the limit of its movement, and allowance is made for variation in the bottles. The inner end of the lever U, which may be provided with an anti-friction-roller u^3 , bears against the cam-shaped rim of a ring V, which is threaded and vertically adjustable upon a cylindrical rim V' on the bottom of the reservoir C. That part of the rim of the ring V with which the levers U engage is so shaped that when a bottle placed on one of the nozzles Q' against the associated rest S is pressed downward and inward the outer end of the lever U will be thrown upward, closing the jaws T against the neck of the bottle and moving them upward in engagement with the shoulder thereon until the mouth of the bottle is tightly pressed into the packing-ring in the head q.

To each arm q^4 or lever U near its fulcrum is pivoted a lever W, which engages at its outer end with the jaws T, limiting their downward movement on the tube t , and at its inner end with a part of the rim of ring V, which is concentric with the trunnions on which the bottle-holders and siphons swing. The thumb-screw s, by which the lever U is pivoted or fulcrumed to the arm q^4 , may serve also as a clamping-screw for holding the bottle-rest S in adjusted position on the arm q^4 , as shown in Figs. 7 and 8. The opening in said rest, through which said screw passes, is transversely elongated to permit of the adjustment of said rest, which is pivotally connected by a pin or stud with the arm q^4 above said opening, the arm and rest being formed below said opening with interlocking teeth or projections.

My improved machine operates as follows: The pipe or hose leading out of the cask or receptacle containing the liquid to be bottled being attached to the liquid-supply connection B, and a pipe or hose leading from a reservoir containing compressed air or gas being attached to the connection L, the cock l is opened and gas under pressure is allowed to pass through the chamber k and tubes J and N into the gas-holding bell M and reservoir C, pressure in said reservoir and bell, which are now in open communication with each other, being the same and indicated by the manometer or gage X. (Shown in Fig. 1.) The cock l is then closed and the liquid to be bottled is admitted through the connection B and tubular stem D into the reservoir C. As it rises therein it immerses and seals the lower edge of the gas-holding bell M, as shown in Fig. 1. The level to which the liquid rises in said reservoir is determined by the volume and pressure of gas contained in the bell or holder M, and these are regulated by means of the cocks l and l' . In practice the reservoir from which gas is supplied to the machine is also connected with the cask or receptacle containing the liquid to be bot-

tled. If the cask or receptacle containing the liquid is placed at about the same level as the reservoir C of the bottling-machine, the same gas-pressure may be supplied to it and to the bottling-machine; but if the liquid-receptacle is placed above the machine it is necessary to provide the connection between the gas-reservoir and the liquid-receptacle with a reducing-valve. In case the liquid does not rise in the reservoir C to the desired level, as indicated by a glass gage, (not shown,) part of the gas entrapped in the bell M is allowed to escape by opening the cock l' , thus reducing the pressure in said bell and allowing it to descend by reason of the greater gas-pressure outside. The descent of the bell opens the waste-valve P and allows some of the gas contained in the reservoir C to escape, thereby reducing the pressure outside of the bell and allowing it to resume its original position and said valve to close. The reduction in the volume of gas contained in the reservoir C and bell M allows the liquid to rise therein. In case the liquid should rise too high the cock l is opened, allowing more gas to pass into the bell M and increase the pressure therein. The bell is thus caused to rise and open the valve H, which admits gas into the reservoir outside of the bell through the tubes G and I and branch passage l^2 , thus increasing the pressure outside of the bell and causing it to descend and the valve H to close. This increased pressure in the reservoir C, both inside and outside of the bell M, causes the liquid-level to fall. Liquid and gas supply connections having been made and the level in the reservoir C adjusted, as above described, the operator, standing on one side of the machine, places a bottle on one of the nozzles Q' against the associated rest S and turns it downward and inward, as shown at the right in Fig. 1. This operation opens the valve R, allowing gas to flow into the bottle around the nozzle Q' until the pressures in the bottle and reservoir are equalized. When the counter-pressure thus produced in the bottle, plus the weight of the valve q, is equal to or slightly greater than the pressure of the liquid, said valve, which was closed and held in that position by the unbalanced liquid-pressure, will be opened, allowing the liquid to flow through the siphon Q Q' into the bottle by gravity. The gas-pressure in the bottle and reservoir being the same, there will be no foam or loss of liquid, no liberation of gas, and no deterioration of the liquid in consequence thereof. In starting the machine when the siphons are empty, each bottle when moved into position is suddenly pulled downward, the spring u^2 permitting a sufficient movement of the bottle to draw enough liquid into the siphon to fill and start it. After the siphons are once filled they will remain so until the reservoir C is emptied. As each bottle is placed in position to be filled it is turned with the reservoir C to one side, another bottle is placed in position, and so on

until all the siphons are supplied with bottles. As the filled bottles return to the starting-point they are turned upwardly and removed from the siphons and replaced by empty bottles. In their passage around the machine ample time is allowed for filling, so that the operator without change of position may remove filled bottles with one hand while he supplies their places with empty bottles with the other hand. Each bottle to be filled is placed by the operator on a nozzle Q' and moved upwardly thereon until its mouth rests against the packing-ring in the head q , the jaws T being spread sufficiently to allow the shoulder on the neck to pass between them. The body of the bottle bearing against the support S is swung downwardly and inwardly, the initial movement thereof causing the cam-ring V to depress the inner end of the lever U and raise its outer end. This movement of the lever U forces the wedge t' upwardly between the lugs t^2 on the rear ends of the jaws, thereby closing the jaws against the neck of the bottle and then carrying them upward with it against the shoulder on the neck of the bottle. The mouth of the bottle is thus forced upwardly into the head q against the packing-ring therein, by which it is sealed. When the neck of the bottle is grasped by the jaws and its mouth is pressed against the packing-ring with sufficient force, the movement of the jaws and their actuating-wedge is arrested and the spring u^3 is compressed, permitting of the further movement of the lever U . The tension of said spring therefore determines the degree of force with which the jaws grasp the neck of the bottle and force its mouth against the packing-ring, and the closing of the jaws, as well as their upward movement, will be arrested whenever, according to the size of the bottle-neck and the distance of the shoulder from the mouth thereof, which vary in different bottles, the resistance opposed to such movements of the jaws is sufficient to overcome the tension of said spring. The springs u^2 are made of such strength or tension or are so adjusted that the jaws will not break or injure the bottles. The wedge t' is forced more or less between the lugs t^2 , according to the diameter of the neck of the bottle grasped by the jaws. The jaws are thus made self-adjusting within certain limits to accommodate the ordinary variation in the necks of bottles of any given size or of different sizes. After the mouth of the bottle is forced against the packing-ring in the head q sufficiently to seal it against the passage of gas the inner end of the lever r is carried by the continued inward and downward movement of the bottle against the upper side of the neck c^2 , thereby raising its outer end and lifting the valve R from its seat, as shown at the right in Fig. 1. Gas thereupon rushes from the upper part of reservoir C into the bottle until the pressure therein equals that in the reservoir. As soon as the pressure in the bottle is equal or

nearly equal to that of the reservoir the valve q' falls away from its seat, allowing liquid to flow from the lower part of said reservoir through the siphon-tube Q and nozzle Q' into the bottle. The parts of the machine being so arranged and adjusted that the mouth of the bottle is at or near the level of the liquid within the reservoir C , the flow of liquid from the reservoir into the bottle will stop when the bottle is filled or nearly filled. The gas displaced by the liquid flowing into the bottle passes back through the annular space in the head q , around the nozzle Q' , and through the passage in the upper part of the siphon-tube Q into the reservoir. Any material variation in the pressure or liquid-level within the reservoir C , which might otherwise result from variations produced by the operation of the machine in the volume of gas contained in the reservoir, is prevented by the automatic operation of the gas supply and waste valves H and P by the movable gas-containing bell M , as hereinbefore explained. When the bottle returns to the starting-point after its passage around the machine, it is swung outwardly and upwardly and withdrawn from the nozzle Q' . The initial movement of the siphon in this direction releases the lever r and the valve R , which thereupon closes the gas-passage in the tube Q before the bottle is released by the jaws T and allowed to move away from the packing-ring in the head q . The further movement of the bottle carries the inner end of the lever U outward against the cam-ring V , thereby allowing the jaws T to descend with the bottle until their movement is arrested by the lever W . The further outward and upward movement of the bottle withdraws the wedge t' from the lugs t^2 , allowing the jaws T to open and release the bottle, which is then withdrawn from the nozzle Q' , leaving it in position to receive an empty bottle. The valve q' , which may be closed or partially closed by the upper end of its stem entering the passage in the siphon when its inner end is turned down, as shown at the left in Fig. 1, is instantly and completely closed and held closed by the unbalanced pressure on its under side as soon as the mouth of the filled bottle is released from the packing-ring in the head q until it is again unseated by the counter gas-pressure produced in another bottle, as above explained.

The sleeves q^2 , extending the inner ends of the siphon-tubes Q when they are lifted, as shown at the right in Fig. 1, insure a supply of liquid to the siphons when the liquid-level in the reservoir is low and serve to remove nearly all the liquid from the reservoir whenever the operation of the machine is to be discontinued.

The machine is adjusted for bottles of different sizes by setting the rests S backward for larger bottles or forward for smaller ones and by screwing the cam-ring V up or down. The latter adjustment simultaneously sets the

jaws T of all the bottle-holders and siphons, the raising of said ring lowering the jaws, while the lowering of the ring raises the jaws.

It will be observed that provision is made 5 for easily and quickly gaining access to the various parts of the machine—as, for example, the siphons may be detached and removed by unscrewing the collars c³, and the valves H and P and the bell M may be reached by 10 removing the cover C'. This is of great importance for bottling beer and similar beverages in order that the machine may be frequently and thoroughly cleansed.

The machine is compact in form, occupying 15 a very small-floor space, is easily and economically operated, and avoids waste and deterioration of the beverage or liquid to be bottled.

I do not wish to be understood as limiting 20 myself to the exact details of construction herein shown and described, as they may be variously modified without materially affecting the operation of the machine or departing from the principle of my invention.

25 I claim—

1. In a bottle-filling machine the combination with a suitable stand or support, of a closed reservoir rotatably mounted thereon and having a number of valve-controlled nozzles, a liquid-supply connection, and gas supply and waste connections; valves controlling said gas connections; and a vertically-movable bell within said reservoir adapted to operate said gas-valves, substantially as and for 35 the purposes set forth.

2. In a bottle-filling machine the combination of a closed reservoir having valve-controlled gas supply and waste connections, one or more valve-controlled bottle-filling siphons 40 or nozzles, and a vertically-movable bell within said reservoir having valve-controlled gas supply and waste connections, and adapted to operate the valves of the gas supply and waste connections of said reservoir, substantially as and for the purposes set forth.

3. In a bottle-filling machine the combination with a suitable stand or support, of a closed reservoir adapted to turn horizontally on said stand or support and having a liquid-supply connection and gas supply and waste 50 connections, siphons pivotally connected with said reservoir, and having gas and liquid passages opening respectively into said reservoir above and below the level of the liquid there-

55 in, valves in said gas-passages adapted to be opened by the movement of said siphons into filling position, valves in said liquid-passages adapted to be automatically opened by counter-pressure of gas, and automatic means for 60 regulating the gas-pressure in said reservoir, substantially as and for the purposes set forth.

4. In a bottle-filling machine the combination with a suitable stand or support having liquid and gas supply connections, of a closed 65 reservoir having a vertically-disposed tubular stem adapted to turn in said stand or support in communication with its liquid-supply

connection, a vertically-movable bell or gas-holder inclosed in said reservoir and having a tubular stem, tubes or passages leading 70 from the gas-supply connections through the tubular stem of said reservoir and opening one into the bell and the other into the reservoir outside of the bell, manually-operated cocks controlling the gas connection which 75 communicates with the interior of said bell, valves normally closing the tube or passage opening into said reservoir, and a waste port or passage opening out of said reservoir and adapted to be operated by the movement of 80 said bell, and valve-controlled siphons leading out of said reservoir, substantially as and for the purposes set forth.

5. In a bottle-filling machine the combination of a closed rotary reservoir adapted to 85 turn on a vertical axis and provided with lateral openings and with liquid-supply and gas supply and waste connections, vertically-swinging siphons pivotally connected with said reservoir and having gas and liquid passages 90 communicating respectively with the interior of said reservoir above and below the level of the liquid therein, said liquid-passages terminating outside in downwardly-projecting nozzles, valves in said gas-passages 95 adapted to be opened by the downward movement of said nozzles, valves in said liquid-passages adapted to be opened by the counter gas-pressure produced in the bottles to be filled, and means for regulating the gas-pressure in said reservoir, substantially as 100 and for the purposes set forth.

6. In a bottle-filling machine the combination of a closed reservoir having liquid-supply and gas supply and waste connections, 105 siphons pivotally connected with said reservoir, and having gas and liquid passages communicating with the interior of said reservoir above and below the liquid-level therein respectively, flexible diaphragms closing the 110 openings between said siphons and reservoir, valves normally closing said gas-passages and adapted to be opened by the movement of the siphons into filling position, valves normally closing said liquid-passages and adapted to be 115 automatically opened by the counter gas-pressure in bottles to be filled when that pressure is approximately equal to the pressure in said reservoir, and means for regulating the pressure in said reservoir, substantially as and 120 for the purposes set forth.

7. In a bottle-filling machine the combination of a closed reservoir having liquid-supply and gas supply and waste connections, 125 valves normally closing said gas supply and waste connections, a vertically-movable bell inclosed in said reservoir and adapted to open said valves, a valve-controlled gas supply and waste connection communicating with the interior of said bell, and valve-controlled gas 130 and liquid passages leading out of said reservoir and adapted to be put in communication with bottles to be filled, substantially as and for the purposes set forth.

8. In a bottle-filling machine the combination of a rotary reservoir provided with bottle-filling nozzles and heads pivotally connected therewith, pivotally-connected jaws adapted to grasp the neck of a bottle placed on said nozzles and movable toward and from said heads, wedges for closing said jaws and moving them toward said heads, levers fulcrumed to arms on said heads and connected with said wedges, and an annular cam or incline adjustably attached to said reservoir and adapted to engage with said levers for operating said jaws, substantially as and for the purposes set forth.
- 15 9. In a bottle-filling machine the combination of a rotary reservoir provided with bottle-holders each pivotally connected therewith and comprising a head provided with an elastic packing-ring, a nozzle passing through said ring and communicating with said reservoir, a rest adjustably connected with said head and adapted to support bottles in the proper relation to said nozzle for filling, pivotally-connected jaws movable toward and from said head and the neck of a bottle placed between them upon said nozzle, a wedge for closing said jaws, a lever pivotally connected with said head and yieldingly connected with said wedge, and a vertically-adjustable cam attached to said reservoir and engaging with the wedge-operating levers of the several bottle-holders, substantially as and for the purposes set forth.
- 25 10. In a bottle-filling machine the combination of a rotary reservoir having liquid-supply and gas supply and waste connections, valves normally closing said gas supply and waste connections, a vertically-movable gas-containing bell inclosed in said reservoir and adapted to open said valves, siphons pivotally connected with said reservoir and having gas and liquid passages communicating with the interior of said reservoir above and below the liquid-level therein, nozzles constituting the outer ends of the liquid-passages of said siphons, packing-rings surrounding said nozzles, pivotally-connected jaws movable toward and from said packing-rings, wedges for closing said jaws upon the necks 35 of the bottles and moving them upward toward said packing-rings, levers having ful-
- erum connections with said siphons and yieldingly connected at their outer ends with said wedges, and a vertically-adjustable annular cam attached to said reservoir and adapted to engage with the inner ends of said levers, substantially as and for the purposes set forth.
- 40 11. In a bottle-filling machine the combination of a rotary reservoir adapted to turn on a vertical axis and having a liquid-supply connection and valve-controlled gas supply and waste connections, means for automatically regulating the gas-pressure and liquid-level in said reservoir, bottle-filling heads pivotally connected with said reservoir and having valve-controlled gas and liquid passages communicating with the interior of said reservoir above and below the liquid-level therein, said heads being provided with elastic packing-rings, pivotally-connected jaws 45 movable toward and from said heads, levers fulcrumed to arms of said heads, wedges yieldingly connected with said levers and adapted by engagement with lugs on said jaws to close the same and to move them upward toward said heads, a vertically-adjustable cam-ring attached to said reservoir and engaging said levers, and stop-levers carried by the arms on said heads in engagement with said cam-ring in position to arrest the downward movement of said jaws, substantially as and for the purposes set forth.
- 50 12. In a bottle-filling machine the combination of a closed reservoir having liquid-supply and valve-controlled gas supply and waste connections, means for regulating the gas-pressure and the liquid-level in said reservoir, siphons pivotally connected with said reservoir and having valve-controlled gas and liquid passages communicating with the interior 55 of said reservoir above and below the liquid-level therein respectively, and sleeves having telescoping connections with the inner ends of said siphons and forming extensions of the liquid-passages therein, substantially as and for the purposes set forth.

In witness whereof I hereto affix my signature in presence of two witnesses.

FRANK C. KELLER.
